Italy

Application November 19, 1953, Serial No. 27,676

Term of patent 14 years

(Cl. D57—1)

To all whom it may concern:

Be it known that I, Elvira Bouyeure, have invented a new, original, and ornamental Design for a Pair of Spectacles or Similar Article, of which the following is a specification, reference being had to the accompanying drawing, forming a part hereof.

Figs. 1, 2, and 3 are front, plan, and side views, respectively, of a pair of spectacles embodying my new design.

The dominant feature of my design resides in the portions illustrated in full lines in the accompanying drawings.

I claim:

The ornamental design for a pair of spectacles or similar article, substantially as shown and described.
